UNITED STATES PATENT OFFICE

HARRY W. PROTZELLER, OF EAST CHICAGO, INDIANA, ASSIGNOR TO O. F. JORDAN COMPANY, OF EAST CHICAGO, INDIANA, A CORPORATION OF INDIANA

RAILROAD SPREADER

Application filed July 26, 1928. Serial No. 295,451.

This invention relates to improvements in railroad spreaders and it consists of the matters hereinafter described and more particularly pointed out in the appended claims.

5 The primary object of the invention is to provide in a railroad spreader, an improved brace construction between the car and main spreader wing and one which may be locked at any point in its extended position to prevent any telescoping of the parts under the great loads imposed upon the wing.

Another object of the invention is to provide a brace construction devoid of any locking pin and hole arrangement so that the 15 parts may have a relative turning during the changing of the vertical angular position of the wing and may be readily locked together irrespective of the vertical angular position of the wing.

20 Still another object of the invention is to provide a telescopic brace for the wing, the parts of which brace may be frictionally locked together and this by a novel arrangement of parts carried by the brace itself.

25 These objects of the invention as well as others, together with many advantages thereof will more fully appear as I proceed with my specification.

In the drawings:—

30 Fig. 1 is a top plan view of a railroad spreader embodying the improved form of wing brace.

Fig. 2 is a detail view in side elevation on an enlarged scale of the associated end 35 parts of the brace and the means for locking said parts together.

Fig. 3 is a transverse vertical detail sectional view on a further enlarged scale as taken on the line 3—3 of Fig. 2.

40 Fig. 4 is a detail view in side elevation of one of the levers embodied in the locking means for the brace.

Fig. 5 is another detail sectional view as taken on the line 5—5 of Fig. 3.

45 Fig. 6 is a horizontal detail sectional view as taken on the line 6—6 of Fig. 5.

Referring now in detail to that embodiment of the invention illustrated in the accompanying drawings, 1 indicates as a whole 50 the car of a railroad spreader and 2—2 in-

dicate the main spreader or side wings; arranged one at each side of the car. In Fig. 1 the decking of the car has been omitted for the purpose of more fully showing the under framing thereof.

Said under framing includes side sills 3—3 suitably connected together and extending from end to end of the car. At the front end of the car and spaced laterally outward from said sills are shorter sills 4—4 thus providing a wider frame or platform part 5 at said end of the car which is pointed in the usual manner to accommodate the associated V shaped front plow 5^a.

At the rear end of the car and spaced laterally from the sills 3—3 are shorter sills 6—6 which are suitably connected together and the front end of each shorter sills 6 is offset inwardly to meet and be secured to an associated sill 3. This provides a wider frame or platform part 7 at the rear end of the car and associated with each platform is a suitable wheel truck 8—8. The construction just above generally described, provides a substantially arrow shaped car body 70 with wider front and rear end parts and a narrower intermediate part, thus forming cut in or recessed sides for the car in which the wings are disposed when the car is in transit from one point of use to another.

At each side of the car, a suitable distance to the rear of the wider front platform part 5 is an upright wing carriage post 9, suitably secured to and supported from the side sills. Each post is preferably tubular and mounted thereon for vertical guided movement is a hinge bracket plate 10. Said bracket is preferably bifurcated to receive the inner end of a wing 2 and said wing is hinged in the bracket plate by a horizontal pin 11. Suitably connected to each post is an arm 12 the free end of which is connected to a piston of a compressed fluid cylinder 13 carried on the car under framing as best shown in Fig. 1. As is apparent in said figure each cylinder is 85 disposed on that side of the car opposite the one upon which its associated wing is located. Thus when fluid under pressure is admitted to one end of a cylinder it will swing the associated wing about its carriage post, away 90 100

from the car as best shown at the bottom of Fig. 1, and when fluid under pressure is admitted to the other end of said cylinder, the wing is swung in toward the side of the car as best shown at the top of said Fig. 1. As 5 the construction just described will form the subject matter of a separate application to be filed later, it will not be described in detail herein.

With each wing is associated a power cylinder 15 by which the wing may be swung into different vertical angular positions about the pin 11 which connects the inner end of the wing to the bracket plate 10. From the above, it is apparent that the wing may be 10 readily swung from an inoperative position parallel with the cut in sides of the car to an operative position at an angle thereto and that when said wing is in its operative position, its outer end may be swung up or down 15 to give the desired vertical angularity thereto.

Associated with each wing is one or more braces, the function of which is to hold the 20 wing in the desired angular position with respect to the car and to receive the thrust or load imposed upon the wing in service and to transmit it to the under framing of the car. Heretofore the braces have been 25 made of telescopic I beam and channel arrangement and in some cases telescopic tubes are employed but in each instance locking pins and holes were provided to lock the braces in the desired extended position. Such 30 arrangements have not proven satisfactory because the position of the locking pin in the desired hole, determined the angular position of the wing and in some instances the correct angle could not be attained because 35 of the location of the pin and hole. Again with the I beam and channel brace, a serious twist was imposed upon the same when changing the vertical angle of the wing and when telescopic tubular members were 40 employed having locking pins and holes, the pin could not always be brought into position with the hole because of the radial angular 45 displacement between the two due to the relative twisting between the tubular brace parts when the vertical angular position of the 50 wing was thus changed.

The present braces, now about to be described, eliminate the objections above noted. As shown in Fig. 1, I provide inner and 55 outer braces 16 and 17 for each wing and as they are substantially alike in structure and only different in length, a detailed description of one will suffice for both.

Each brace includes inner and outer tubular members or pipes 18 and 19 respectively. In this instance the inner pipe member 18 is of a larger diameter, and on the outer 60 end thereof is fixed a clamp guide casting 20 with a reduced end sleeve 21 in which the 65 inner end of the outer brace member 19 has

a snug fit that will permit of a longitudinal as well as a turning movement of said member in said sleeve. Preferably this casting is 70 removably secured to the outer end of the inner brace member by bolts 22—22 as best shown in Figs. 3 and 5 respectively and in the top and bottom sides of said casting are 75 rectangular openings 23 and 24 respectively which register with similar openings in the pipe 18. On that end of the pipe 19 which telescopes within the pipe 18 is fixed a collar 25 having a snug sliding fit with the interior surface of the pipe 18, to coact with the sleeve 21 and thus provide the proper bearing 80 between the pipes 18 and 19.

Disposed within the pipe 18 so as to partially surround the pipe 19, are top and bottom clamping blocks or shoes 26 and 27 respectively, each of which has a central portion 26^a—27^a respectively which extend 85 through the openings 23 and 24 respectively, before mentioned. The central portion 27^a of the bottom block or shoe 27 is formed to provide a downwardly facing boss 28 that 90 engages in a seat 29 on a transversely disposed pressure bar or beam 30. In the boss 28 is a vertically disposed opening 31 which registers with a similar opening 32 in the pressure beam 30. The opening 31 is of a peculiar 95 formation in that its bottom end is made as a transversely extending slot 31^a while the top end is enlarged to provide a shoulder 31^b and in said shoulder at opposite sides of the slot are recesses 31^c—31^d. A T shaped bolt 33 connects the said block and pressure beam together and the top end of said bolt has a head 33^a which is transversely elongated so that 100 it may be inserted up through the slot 31^a and then turned to engage in the recesses 31^c, there being a nut 34 on the bottom end of the 105 bolt for the purpose readily apparent. When necessary as when the braking or gripping surface of the block becomes worn, the same may be taken up or compensated therefor by placing one or more shims 35 between the boss 110 28 and seat 29.

In the central portion 26^a of the block or shoe 26 is a recess 26^b which receives the stem 36 of an upright pressure post 37, a pin 38 securing the stem in place in said recess. The 115 top end of said post has a transversely extending opening 39 in which is journaled a stub shaft 40 and to the end extensions of said shafts are secured depending links 41—41.

The pressure beam 30 has end trunnions 120 30^a—30^a and journaled thereon are the bottom ends of substantially upright links 42—42, the mid portions of which have guided bearing between longitudinally spaced lugs or shoulders 43—43 on each side of the 125 bracket casting 20 as best shown in Figs. 2 and 3.

Associated with said links is a pair of levers 44—44. Each lever is provided at its bottom end with laterally extending, oppo- 130

sitely and eccentrically disposed inner and outer trunnions 45 and 46 respectively. As best shown in Fig. 4, the said trunnions are offset along a plane at less than a right angle to the longitudinal plane of the lever itself. The outer trunnion of each lever bears in a suitable opening in the top end of an associated link 42 while the inner trunnion of each lever bears in an opening in the bottom end of an associated link 41 as best shown in Fig. 3. The top ends of the levers 44—44 are connected by a cross shaft 47 and on said shaft between said levers is journaled a T shaped cross head 48.

Secured to the pipe 18 a suitable distance inwardly from the casting 20, is a clamp like bracket 49 which includes a pair of upwardly extending arms 49^a—49^a. Associated with this bracket is a cylinder 50 having front and rear end heads 51—52 respectively and in this instance the rear end head is pivoted by a pin 53 to and between the bracket arms 49^a—49^a. A piston rod 54 slides through the front end head 51 and one end thereof carries a piston 55 disposed in the cylinder while the other end of said rod is connected to the crosshead 48 before mentioned. Suitable pressure fluid inlet and outlet 56 and 57 respectively are fixed in said heads so that motive fluid under pressure may be admitted to either end of the cylinder to move the piston in the desired direction. The said inlet and outlet lead from a suitable source of supply located upon the car where usual valve mechanism (not shown) for controlling said inlet and outlet are also located.

The outer or free end of the pipe 19 has a ball and socket joint connection with the rear side of the wing as indicated as a whole at 58 in Fig. 1 while the inner end of the pipe 18 has a universal joint connection with the under framing of the car as indicated as a whole at 59 in said figure. The ball and socket joint connection 58 is such as will permit a turning movement of the pipe 19 with respect to the wing without a separation therebetween while the universal joint connection is such as will permit the brace as a whole to swing in toward or out away from the car as well as upwardly or downwardly. Said universal joint, however, will not permit a turning or twisting of said pipe with reference to said car under framing.

The operation of the mechanism above described is as follows:—

Assume that both wings are folded in toward the car as shown at the top of Fig. 1. When it is desired to swing one of the wings into an operative position as shown at the bottom of Fig. 1, air is admitted to the proper cylinder 13 which through the associated arm 12 will swing said wing into its operative position about the associated wing post as an axis. In this movement of the wing, the pipe section 19 will slide in the pipe section

18, it being understood that no motive fluid under pressure is in the cylinders and that the levers 44 stand in the position of minimum load as indicated in dotted lines in Fig. 2 at which time the shoes or blocks 26—27 are exerting no pressure or gripping action on the pipe 19.

When the desired operative angular position of the wing has been reached, fluid under pressure is admitted through the conduit 56 to the rear end of the cylinder 50, fluid in advance of the piston 55 therein passing out through the conduit 57 and through the valve mechanism on the car to atmosphere. As the piston moves forwardly, the levers 44 are swung into the maximum load position shown in full lines in Fig. 2. As the levers thus move into said position, the eccentric trunnions on their bottom ends will produce an upward movement of the links 42 and associated parts and a downward movement of the links 41 and associated parts thus causing the blocks or shoes to frictionally clamp or lock upon the pipe 19 to lock it to the pipe 18. It has been demonstrated in actual use that by clamping or frictionally gripping the blocks 26—27 upon the pipe as described, the brace may be held in its extended condition under far greater load strains imposed by the wing than was heretofore possible to hold with the pin and hole type of lock previously employed. Should the wing tend to float up or down due to the uneven surfaces operated upon, or if it becomes necessary to change the vertical angle of the wing, for any reason, this is possible after unlocking the pipe 19 and should the pipe 19 turn during this operation, it will in no manner interfere with the relocking because on registration of locking pin and hole need be taken into consideration.

When it is desired to swing the wing back into its inoperative position along side of the car, the fluid is shut off from the cylinder 50 thus releasing the gripping action on the pipe 19 and as said wing swings inwardly the pipe 19 is free to slide in the pipe 18 and thus telescope and foreshorten as is necessary.

Should the pipe engaging surface of the bottom gripping block or shoe become worn, the links 42—42 are removed, and the nut is unscrewed from the bolt 33 so that the pressure beam may be removed to permit insertion of additional and wear compensating shims between the boss 28 and seat 29 after which the parts removed are replaced.

The construction described has many advantages. It securely holds the brace in its extended position under extreme loads and the gripping blocks or shoes grip upon any place necessary upon the pipe 19. The parts employed are strong and rigid and easily accessible for inspection when necessary and cannot readily get out of order.

While in describing my invention I have

referred in detail to the form and arrangement of the parts thereof, the same is to be taken as by way of illustration only and I do not wish to be limited thereto except as may be more specifically pointed out in the appended claims.

I claim as my invention:

1. In combination with coacting tubular telescopic members, a guide on one of said members, means movable in said guide at a right angle to one of said members and extending at least part way around the other member and conforming to the associated surface thereof and adapted to be moved into engagement therewith to frictionally hold said members against relative movement.
2. In combination with two coacting tubular telescopic members, a guide on one of said members, means movable in said guide at a right angle to one of said members and extending at least part way around the other member and conforming to the associated surface thereof and adapted to be moved into and out of such frictional engagement with said surface of the other of said members as to lock them together and means for imparting such movement to said first mentioned means.
3. In combination with a pair of coacting tubular telescopic members, a guide on one of said members, a plurality of friction blocks mounted in said guide and having surfaces conforming with and partly surrounding portions of the other of said members and adapted to engage therewith, and means for simultaneously imparting movement to said blocks in said guide to bring said surfaces into and out of engagement with said portions of the other of said members.
4. In combination with a pair of coacting inner and outer tubular telescopic members, a guide on the outer telescopic member coacting gripping blocks having portions partly surrounding the inner member and adapted to be moved in said guide in the same plane toward and away from opposite sides of said inner member and into and out of frictional engagement therewith and means for imparting simultaneous movement to said blocks.
5. In combination with a pair of coacting inner and outer tubular telescopic members, coacting gripping blocks having portions partly surrounding the inner member and adapted to be moved in said guide in the same plane toward and away from opposite sides of said inner member into and out of frictional engagement therewith, an actuating member common to both gripping blocks and means for connecting said actuating member and blocks for moving said blocks in opposite directions toward and away from said inner member to frictionally secure and release the same from the outer member.
6. In combination with a pair of coacting inner and outer tubular telescopic members,

coacting gripping blocks having portions partly surrounding the inner member and conforming to the exterior surface thereof, which blocks are adapted to be moved in the same plane in said guide toward and away from opposite sides of said inner member, an actuating member common to both gripping blocks and means including opposed eccentric devices arranged outside of said guide for connecting said actuating member and blocks for moving them in opposite directions toward and away from and into and out of frictional locking engagement with said inner member.

7. In combination with a pair of coacting inner and outer tubular telescopic members, coacting gripping blocks having portions partly surrounding the inner member and conforming to the exterior surface thereof, which blocks are adapted to be moved in the same plane in said guide toward and away from opposite sides of said inner member, a lever common to both gripping blocks and having opposed eccentric devices thereon and links arranged outside of the guide for operatively connecting each block with one of said eccentrics.

8. In combination with inner and outer telescopic tubes, a guide casting on the outer tube, a frictional gripping member movable in said casting and having a portion partially surrounding and conforming to the exterior surface of the inner tube to frictionally grip upon said inner tube, and power means on said outer tube for actuating said member in one direction in said guide to frictionally grip upon said inner tube.

9. In combination with inner and outer telescopic tubes, a guide casting on the outer tube, a frictional gripping member movable in said casting and having a portion partially surrounding and conforming to the exterior surface of the inner tube to frictionally grip upon said inner tube, a lever operatively connected to said gripping member and a power actuated device mounted on said outer tube for actuating said lever.

10. In combination with inner and outer telescopic tubes, a guide casting on the outer tube, a frictional gripping member movable in said casting and having a portion partially surrounding and conforming to the exterior surface of the inner tube to frictionally grip upon said inner tube, a lever operatively connected to said gripping member, and a power cylinder pivoted at one end to said outer tube and including a piston rod at its other end connected to said lever.

In testimony whereof, I have hereunto set my hand, this 13th day of July, 1928.

HARRY W. PROTZELLER.
